WINDOW CONSTRUCTION

Hans Mockli, Hawthorne, N. J.

Application May 28, 1938, Serial No. 210,560

9 Claims. (Cl. 20—42)

The present invention relates to window constructions of the type, in which the lower or inner window sash is slideable along sash tracks, and swingable about pivotal supports.

5 One object of the present invention is to provide simple and improved means for pivotally supporting a window sash, to a window frame.

Another object is to provide simple and effective means for pivotally supporting and holding 10 sash tracks in angular position against rattling.

Another object is to provide simple and improved means for holding the window sashes in selective slide positions, and against rattling, without the use of the usual sash weights.

15 Another object is to provide sash tracks of simple, rugged and inexpensive construction.

Another object is to provide simple, effective and easily manipulable means for locking pivotally mounted sash tracks in vertical position, 20 against swingable movement.

Another object is to provide simple, easily removable cross-bracing means for a pair of opposed pivotally supported sash tracks.

Various other objects and features of the 25 invention will be apparent from the following particular description, and from an inspection of the accompanying drawings, in which:

Fig. 1 is a perspective of a window construction embodying the present invention, and showing the sash tracks interlocked, and the window sashes in vertical closed position.

Figs. 2 and 3 are sections taken on lines 2—2 and 3—3 of Fig. 1 respectively.

Fig. 4 is a section taken on line 4—4 of Fig. 3, 30 but on a somewhat enlarged scale.

Fig. 5 is a section taken on line 5—5 of Fig. 2 on an enlarged scale, and shows details of the means for locking the lower sash tracks in vertical position.

40 Fig. 6 is a perspective showing a portion of the lower window sash.

Fig. 7 is a front perspective view of one of the lower sash tracks.

Fig. 8 is a rear perspective view of the sash 45 track of Fig. 7.

Fig. 9 is a front perspective view of one of the upper sash tracks.

Fig. 10 is a section taken on line 10—10 of Fig. 7, but on a somewhat enlarged scale.

50 Fig. 11 is a perspective showing the removable cross-piece for the lower end of the lower sash tracks.

Fig. 12 is a section taken on line 12—12 of Fig. 2, but shown on a somewhat enlarged scale.

55 Fig. 13 is a detail vertical section showing one of the lower sash tracks in one angular position, and

60 Fig. 14 is a section similar to that of Fig. 3, but showing the lower sash tracks in another limited angular position.

In the form of the invention illustrated, there is provided a frame window 10, having a lintel 11 at the top, a sill 12 at the bottom, and upright jamb pieces 13 at the sides. Upper vertical sash tracks 14 are affixed to these jamb pieces 13 respectively by any suitable means, such as screws 15, and the lower sash tracks 16 are pivotally mounted to said jamb pieces, by means of pivot pins 17, as will be hereinafter more fully described, so that said lower tracks can be brought 5 into vertical alignment with said upper tracks, or swung out of the plane of the window frame. The meeting or adjoining ends 18 of the two sets of sash tracks 14 and 16 are conformably bevelled, as shown in Fig. 2, to permit angular movement 10 of the lower tracks 16, and to afford continuity 15 between the two sets in their vertically aligned positions.

As a feature of the present invention, each of the lower tracks 16 comprises a longitudinal strip 20 of metal 20 (Figs. 7 and 10), stamped to form a pair of adjoining channels 22, separated by a central U-shaped rib 23. Welded or otherwise secured in each channel 22 is an inset, stamped from sheet metal to form a U-shaped sash rail 25, dividing said channel into a pair of adjoining guide grooves 26, and having a pair of outward flanges 27a, seated against the base of said channel. By means of this construction, each of the lower tracks 16 will have two rails 25 to receive 30 the respective window sashes 27 and 28, separated by the rib 23.

The upper tracks 14 are constructed of sheet metal in the same way as are the lower tracks 16, to provide on each one a central rib 23a, and 35 a pair of sash rails 25a, these being in alignment with the corresponding central rib 23, and sash rails 25 of the lower track, when the latter is in vertical position, to permit the slideable movement of window sashes 27 and 28 from top 40 to bottom of the window frame. The stiles 29 of these window sashes are provided with outer side grooves 30 (Fig. 6), each defining a pair of opposed flanges 31, adapted to straddle the respective rails 25 and 25a.

45 In order to avoid the use of conventional sash weights, and to provide frictional means whereby the window sashes 27 and 28 may be held in slide position on the sash tracks, each of the stile grooves 30 has fixed therein a pair of spring devices, each including a pair of bowed leaf springs 32, lapped against the inner sides of the stile flanges 31, and integrally joined by a cross-piece 33, which is seated against the base of the groove 30, and which is secured thereto by screws or the like. These leaf springs 32 frictionally engage the sides of the rails 25 and 25a to hold the window sashes in slide position, and since the rattling of these sashes is due primarily to the play of said sashes transversely of the planes thereof, 55 60

these springs 32 will also serve to hold said sashes against rattling.

For pivotally mounting the lower tracks 16 to the jamb pieces 13, the lower portion of each of said pieces has fixed into a recess therein a metal plate 35, to which is secured a nut 36 (Figs. 4 and 12) on its inner side, by welding or the like. The pivot pin 17, provided with an enlarged head 37, is threaded in the nut 36. Each of the tracks 16 has an elongated slot 38 (Figs. 8, 13 and 14), with a central enlarged section 40, just large enough to permit the head 37 of the pivot pin to pass therethrough. The lower portions of the rail flanges 27a are cut away at 40a, to clear the head of the pivot pin 17, as shown in Figs. 4 and 12. In normal upright or angular position of the lower tracks 16, the pivot pins 17 pass through the upper ends of the respective slots 38, as shown in Fig. 13. These pivot pins 17 can be adjusted to tighten the lower tracks 16 against undesirable play.

In order to hold the lower tracks 16 against rattling in their angular position, there is provided a pair of side weather strips 41 of wood or the like, fixed to the respective jamb pieces 13, and abutting the outer edges of the upper tracks 14 (Figs. 2, 13 and 14). The lower ends of these strips 41 extend below the upper sash tracks 14 and above the window sill 12, and are desirably covered respectively with metal wear plates 43, as shown in Figs. 13 and 14. Connected to each of the side flanges 44 of the lower tracks 16 is a bowed leaf spring 45, fixed at its ends by soldering or the like to its respective track flange 44, and yieldably engaging the lower metal covered end of its respective weather strip 41 in angular positions of said tracks 16, to hold said tracks in said positions, while permitting angular movement thereof. These strips 41 also serve as limiting stops, to align the lower tracks 16 with the upper tracks 14 in the upright position of said lower tracks, as shown in Figs. 2 and 3. Also, the lower edges of the tracks 16, beyond the springs 45 engaging the lower ends of the strip 41, will hold said tracks in limited angular position.

If it is desired to swing the lower tracks 16 to a horizontal position, in which the glass panes of the sashes are easily accessible for washing, these tracks are pulled outwardly, so that the pivot pins 17 pass through the lower portions of the elongated slots 38. In this position, the lower tracks 16 are clear from the lower ends of the strips 41, and said tracks will be free to move angularly into the horizontal position shown in Fig. 14. In this position, the window stool 46 serves as a limiting stop for the lower tracks 16.

Fixed to the window frame 10, and abutting the inner edges of the upper tracks 14, is a pair of side weather strips 51 of wood or the like, the lower ends of which terminate substantially at the lower ends of said tracks. Fixed to the inner edge of each of the lower tracks 16 is a weather strip 52, corresponding in cross-section to that of the upper weather strip 51. The meeting or adjoining ends 53 of these strips 51 and 52 are conformably bevelled, as shown in Fig. 1, to permit angular movement of said strips 52, while affording continuity between said strips 51 and 52 in their aligned position.

In order to affix the weather strips 52 to the respective lower tracks 16, each of said tracks has welded or otherwise secured thereto a pair of lugs 54, extending in notches 55 of the corresponding strips 52, as shown in Figs. 1, 7, 8 and

10. Passing through the strips 52, and threaded into the lugs 54, are the screws 56.

Extending along the window stool 46, is a weather strip 57, spaced at its ends from the jamb pieces 13, to provide a clearance for the angular movement of the lower tracks 16, as shown in Figs. 1, 13 and 14.

Connecting the lower ends of the two lower tracks 16, so as to utilize these tracks, is a cross-piece 60 (Figs. 2, 4 and 11), stamped from a single sheet of metal to form a hollow U-shaped rib 61, and formed with a pair of notches 62 at the ends to receive the central track ribs 23. The lower ends of the tracks 16 are provided with transverse flanges 63, upon which the cross-piece 60 may be seated, and said cross-piece has a projecting pin 64 welded or otherwise fixed in one end of the rib 61, and adapted to be slipped into a hole 66 of a rail 25, and a slide bolt 67 in the other end of said rib, adapted to slide in a hole 66a 20 of an opposed rail 25. This slide bolt 67 has an offset handle 68, projecting through an elongated slot 69 in the rib 61. By means of this construction, the two lower tracks 16 may be swung about their pivotal support as a unit, even when the sashes 27 and 28 have been removed to permit detachment of said tracks from the window frame.

In order to prevent the rib 61 and the slide bolt handle 68 from interfering with the sliding 30 of the inner window sash 27 to the bottom of the window opening, the bottom of said sash has a groove 70 (Figs. 4 and 6) and a hole 71 into which extend said rib and said handle 68 respectively in the lowermost position of said sash.

The window sill 12 is inclined, as shown in Figs. 2, 13 and 14 to drain rain water and the like to the outer side of the window opening, and the lower ends of the lower tracks 16 are correspondingly inclined, and extend substantially to 40 said sill, so that the cross-piece 60, in the upright position of said tracks, will lie substantially flat against said sill, as shown in Fig. 2, and serve also as a protective covering for said sill.

In order to lock the lower tracks 16 in the upright position shown in Fig. 1, each of the hollow ribs 23a of the upper tracks 14 has a slide bolt 75 (Figs. 2, 5 and 9), having a transverse knob 76, extending through an elongated slot 77 in said rib. Since the rib 23a of each upper track 14 is aligned with the corresponding rib 23 of the lower track 16 in the upright position of the latter, as shown in Fig. 1, when the slide bolts 75 are moved downwardly through manipulation of their knobs 76, the projecting ends of said bolts will extend 55 into the lower ribs 23, and thereby lock the lower tracks 16 against angular movement. In order to permit the lower tracks 16 to be locked in slightly tilted position with respect to the window frame, the lower ends of the slide bolts 75 are 60 adapted to slide into the outer rails 25 of said lower tracks, when said rails are directly below said bolts. For that purpose, the lower projectable ends of the bolts are reduced in width to correspond to the widths of the rails 25. In order 65 to reduce the cross-section of the lower ribs 23, so that the reduced ends of the bolts 75 have no extensive free play therein, there is welded or otherwise secured into each of said ribs 23, a U-shaped inset 78 (Fig. 10), which not only serves 70 to form with one wall of the rib a housing for snugly receiving its corresponding slide bolt, but also serves to impart rigidity to the lower tracks. If desired, instead of making the width of the rib 23 greater than that of the rail 25, it may be the 75

same, so that the lower ends of the slide bolts 75 need not be reduced as indicated.

The slide locking bolts 75 being operable only from the inner side of the window construction, 5 when the sashes 27 and 28 are in closed position, shown in Fig. 1, unauthorized tampering therewith from the outside is assured. Also these bolts 75 are in position to be almost concealed from view, so that they do not mar the appearance 10 of the window construction.

In the operation of the described window construction, the lower tracks 16 may be locked in upright position, as shown in Fig. 1, and in the manner already indicated, so that the two window 15 sashes 27 and 28 may slide up and down. The two windows may be locked in this vertical position against sliding movement by the conventional sash lock 80. If it is desired to retain the window sash 28 in its uppermost position, and incline the 20 lower window sash 27, the slide bolts 75 are moved upwardly, and said window sash 27 pulled angularly outwardly. If it is desired to move both of the window sashes 27 and 28 into angular position, these are lowered to their lowermost position, 25 between the lower tracks 16, and then angularly pulled out, as already indicated. If it is desired, for instance, to install a window screen 81, both of the window sashes 27 and 28 may be lowered onto the lower tracks 16, and said tracks 30 with the window sashes therebetween moved out angularly to permit the individual sashes to be slid out from between said tracks. This not only permits the easy installation of the screen 81, but also enables the window panes of the sashes to be 35 cleaned in an expeditious manner without the usual toil. In the summer, when it is desired to obtain the maximum amount of ventilation, both of the window sashes 27 and 28 may be removed from the tracks 16, as already indicated. Also, 40 if it is desired to remove the lower sash tracks 16, this can be effected in a very simple manner.

As many changes could be made in the above construction, and many apparently widely different embodiments of this invention could be 45 made without departing from the scope thereof, it is intended that all matter contained in the above description or shown in the accompanying drawings shall be interpreted as illustrative and not in a limiting sense.

Having thus described my invention, what I 50 claim as new and desire to secure by Letters Patent is:

1. A window construction, comprising a window frame, having side jamb pieces, and a sill, a pair 55 of opposed metal sash tracks pivotally supported near their lower ends to said jamb pieces respectively, and a metal cross-piece carried by the lower ends of said tracks, movable therewith in the pivotal movement of said tracks, and forming 60 a protective covering for said sill in the upright position of said tracks, transverse flanges on said tracks at their lower ends limiting the downward movement of said cross-piece, and locking means connecting the ends of said cross-piece and said tracks, and releasable to permit removal of said cross-piece from said tracks upwardly and away 65 from said flanges.

2. A window construction, comprising a window frame, having side jamb pieces, and a sill, a pair 70 of opposed metal sash tracks, pivotally supported near their lower ends to said jamb pieces re-

spectively, and a metal cross-piece for said tracks, having a lug at one end for engagement in a hole in the lower end of one of said tracks, and a slide bolt at the other end for engagement in a hole at the lower end of the other track. 5

3. A window construction, comprising a pair of opposed pivotally supported sash tracks, a fixed member on the outer sides of said tracks, and engaging the outer edges of said tracks in upright position thereof to serve as a stop for said tracks in said position, and spring means between one of said tracks and said member for resisting angular movement of said tracks. 10

4. A window construction, comprising a pair of opposed upper sash tracks, a pair of lower pivotally supported opposed sash tracks, a strip along the outer edge of one of said upper tracks, and extending below the lower end of said latter track for aligning the lower tracks with the respective upper tracks in the upright position of said lower tracks, and means between the lower end 20 of said strip and one of said lower tracks for resisting while permitting angular movement of said tracks. 25

5. A window construction, comprising a pair of opposed pivotally supported sash tracks, a fixed member, and a bowed leaf spring secured at its ends to the outer edge of one of said tracks, and engaging said member to resist said pivotal movement. 30

6. A window construction, comprising a pair of opposed upper sash tracks, a pair of lower pivotally supported opposed sash tracks, a pair of strips along the outer edges of said upper tracks respectively, and extending below the lower tracks 35 with the respective upper tracks in the upright position of said lower tracks, and spring means between the outer edges of said tracks and the lower ends of said strips respectively, for resisting pivotally movement of said tracks. 40

7. A window construction of the type having a window sill, and comprising a pair of opposed sash tracks, pivotally supported near their lower ends, a cross-piece mounted across the lower ends of said tracks, extending closely adjacent to said sill in upright position of said tracks, and movable therewith in the pivotal movement of said tracks, and releasable locking means for locking said cross-piece to said track ends, and means preventing downward movement of said cross-piece endwise of said tracks when said locking means is released, but permitting removal of said cross-piece upwardly while said tracks are in angular position. 45

8. A window construction comprising a pair 55 of opposed sash tracks pivotally supported near their lower ends, and each having a transversely inwardly extending flange at said ends, and a cross-piece removably secured to the lower ends of said tracks, seated on said flanges, and movable with said tracks in their pivotal movement. 60

9. A window construction comprising a pair of opposed sash tracks pivotally supported near their lower ends, and each having a longitudinally extending rib, and a transversely inwardly extending flange at its lower end, and a cross-piece removably secured to the lower ends of said tracks, seated upon said flange, and having notches at its ends for receiving said ribs. 65
